UNITED STATES PATENT OFFICE.

JOHN E. GLIDDEN, OF BEVERLY, MASSACHUSETTS, BY SADIE E. GLIDDEN, GUARDIAN;
SAID SADIE E. GLIDDEN, ADMINISTRATRIX OF SAID JOHN E. GLIDDEN, DECEASED,
ASSIGNOR TO UNITED SHOE MACHINERY COMPANY, OF PATERSON, NEW JERSEY,
A CORPORATION OF NEW JERSEY.

SCOURING-MACHINE.

1,126,749.

Specification of Letters Patent.

Patented Feb. 2, 1915.

Application filed July 30, 1910. Serial No. 574,696.

To all whom it may concern:

Be it known that JOHN E. GLIDDEN, of Beverly, in the county of Essex and State of Massachusetts, insane, invented certain 5 Improvements in Scouring-Machines, of which the following description, in connection with the accompanying drawings, is a specification, like reference characters on the drawings indicating like parts in the 10 several figures.

This invention relates to abrading machines and is herein illustrated as embodied in a machine for scouring the margin of an ornated top lift.

15 It is customary with some manufacturers to make use of top lifts which are ornated by having impressed upon the tread face thereof a design of some sort, said design being ordinarily imparted to the top 20 lift during the compressing operation. When, however, such a top lift has been incorporated into a shoe and it becomes necessary to scour the row of slugs with which a portion of the margin of the top 25 lift of a finished shoe is loaded, a difficulty arises owing to the fact that the ordinary scouring wheel cannot be kept from contact with, and consequent marring of, the ornated portion of the top lift.

30 Accordingly, the general object of the present invention consists in the provision of a machine whereby the marginal surface of top lifts or similar articles may be scoured without danger of injury to the remaining surface.

In the illustrated embodiment of the invention a scouring disk is mounted upon a rotatable shaft, and a guard is provided for the edge of the heel so that a marginal area 40 of a predetermined width only will be scoured, the arrangement of parts insuring that the scouring member shall not contact with the central area of the lift. Preferably the guard takes the form of a disk which is 45 concentric with the scouring disk and is rotatably mounted upon the shaft which actuates the scouring disk so that said guard may remain stationary while a heel is being pressed against it.

50 These and other features of the invention including certain details of construction and combinations of parts will be described in

connection with an illustrative machine and pointed out in the appended claims.

Referring now to the accompanying 55 drawings,—Figure 1 is a perspective of a machine embodying the invention; Fig. 2 is a plan view of the upper tool with its shoe support, a top lift being shown in the position which it occupies during the scouring 60 operation; Fig. 3 is a section on the line 3—3 of Fig. 1, the heel of a shoe being shown in the position which it occupies during the scouring operation; and Fig. 4 is a perspective showing an ornamented top 65 lift.

Rising from a plate 1 which is fastened by bolts 5 to a base 7 is a standard 9 having two arms 11 and 13. At its forward end the arm 11 is formed with a yoke 15 having 70 alined bearings 17 and 19 in which is rotatably mounted a shaft 21 which is provided with a pulley 23 around which passes a belt 25, said belt also passing over two guide pulleys 27 fast to a shaft 29 and being 75 driven from any suitable source of power. The lower end of the shaft 21 has a reduced portion 31 and a shoulder 33, the lower end of the reduced portion being threaded and carrying a nut 35 which bears against a 80 washer 37. Above the washer is a support 39 which may be of any suitable contour and is herein shown as disk-shaped. Above the support 39 is a disk 41 of yielding material, for example felt; and above the felt 85 disk is a disk of abrasive material 43 herein shown as a piece of sandpaper. A clamping member 45 also shown as a disk contacts with the abrasive disk, and a shim 47 is placed between the clamping disk 45 and 90 the shoulder 33. With this construction, if a heel lift were placed with its edge against the clamping member 45 as a guide and the parts thus far described were rotated, there would be danger that the edge of the guide 95 would burn the edge of the heel or otherwise mar its appearance. In order to prevent such possible injury, a guard 49 in the form of a metal disk is mounted upon the shaft 21, said guard being freely rotatable 100 by reason of the fact that it is spaced by the shim 47 from the clamping member 45 and is not clamped between the shoulder 33 and the nut 35. With this construction,

when a heel is placed in position to be scoured, the guard 49 remains stationary while the scouring tool revolves. A support 51 for the heel of the shoe is fast to a rod 53 which is slideable in a bracket 55 and carries lock nuts 57 by which it may be held in adjusted position, said position being preferably such that the plane of the supporting surface coincides with the plane of the abrading surface of the scouring tool.

10 The illustrative machine is provided with a second scouring tool, guard and support located at the upper end of the shaft 21, these elements, however, being similar to 15 those of the lower tool, guard and support except for the small changes necessitated by the different relative positions of said parts with respect to the shaft 21. The parts of the upper scouring mechanism have been 20 given reference numerals which differ by one hundred from those applied to the corresponding parts of the lower mechanism.

In Fig. 4 there is shown at 400 an ornamented top lift having a plain margin to 25 receive the row of slugs. In Fig. 3 there is shown at 300 a heel provided with such a top lift, said heel being in the position it occupies during the scouring operation.

In the operation of the machine, power 30 having been applied to the belt 25 and the supports 51 and 151 having been properly adjusted, a heel is presented to either tool after the manner shown in Figs. 2 and 3. Or if desired, the tools may be fitted with 35 sandpaper of different degrees of coarseness and the lift may be applied to the tools successively. The heads of the row of slugs may thus be scoured without marring the ornamented center of the top lift.

40 Although the invention has been set forth in connection with a particular machine, it should be understood that the invention is not limited in the scope of its application to the particular machine shown and described.

45 Having thus described my invention, what I claim as new and desire to secure by Letters Patent of the United States is:—

1. A machine for scouring the marginal portion of a piece of stock, having, in combination, an abrading tool comprising a supporting member having a flat face, an abrasive member, means for clamping said abrasive member to said supporting member, a guard rotatable with respect to said 50 abrasive member extending partially over said abrasive member and means for actuating said tool.

60 2. A machine for scouring the marginal portion of a piece of stock, having an abrading tool provided with a flat abrading surface of circular outline and a guard rotatable independently of said tool, in combination with a work rest having its operative face in substantially the plane of the abrading surface of the tool.

3. A machine for scouring the marginal portion of a piece of stock, having an abrading tool provided with a flat abrading surface of circular outline, in combination with a work rest having its operative face in substantially the plane of the abrading surface of the tool and means for adjusting said work rest.

4. A machine for scouring the marginal portion of a piece of stock, having, in combination, an abrading tool provided with an annular abrading surface all points of which are substantially in a common plane, a guard having a square edge to engage the edge of the piece of stock located wholly inside said annular surface and means for rotating said tool.

5. A machine for scouring the marginal portion of a piece of stock, having, in combination, a scouring tool comprising a rigid 85 disk, a yielding disk, a disk of abrading material, a clamping member and a shim, said disks, member and shim being superposed, a shaft having a reduced portion which passes through said disks and shim, 90 and having a shoulder which bears against said shim, a nut between which and said shoulder said disks are clamped, a disk-shaped guard of less diameter than the disk of abrading material mounted on said shaft 95 whereby only a predetermined extent of stock may be acted upon by said scouring tool, and means for rotating said shaft.

6. A machine for scouring the marginal portion of a piece of stock, having, in combination, a scouring tool comprising a rigid disk, a yielding disk, a disk of abrading material, a clamping member and a shim, said disks, member and shim being superposed, a shaft having a reduced portion which 100 passes through said disks and shim, and having a shoulder which bears against said shim, a nut between which and said shoulder said disks are clamped, a disk-shaped guard of less diameter than the disk of abrading material rotatably mounted on said shaft whereby only a predetermined extent of 105 stock may be acted upon by said scouring tool, a work rest having its supporting face substantially in the plane of the abrading 11 surface, and means for rotating said shaft.

7. A machine for scouring the marginal portion of a flat piece of stock having, in combination, an abrading tool provided with a flat abrading surface, a guard extending 115 partially over said surface, a work rest having its operative face in substantially the plane of the abrading surface of the tool and means for actuating said tool.

8. A machine for scouring the marginal portion of an ornamented top lift having, in combination, an abrading tool provided with a flat abrading surface, a guard rotatable with respect to said tool extending 120 partially over said surface and leaving ex- 11

- posed only an annular area of said surface, the width of which is equal approximately to that of the unornamented margin of said top lift, and means for rotating said tool.
- 5 9. A machine for scouring the marginal portion of an ornamented top lift having, in combination, an operating tool provided with a flat abrading surface, a guard having a square edge to act as a gage for the edge
- 10 of the top lift, said guard extending partially over said surface and leaving exposed a marginal area of said surface the width

of which is approximately equal to that of the unornamented margin of said top lift, and means for rotating said tool.

15

In testimony whereof I have signed my name to this specification in the presence of two subscribing witnesses.
